UNITED STATES PATENT OFFICE

2,238,769

WALL SUPPORT FOR FLOOR SYSTEMS

Morris Berman, New York, N. Y.

Application August 2, 1938, Serial No. 222,611

4 Claims. (C.I. 72—108)

This invention relates to building construction, and particularly to the connection between concrete floor slabs or steel floor girders to a masonry wall.

It is well known that when a beam or girder is framed into a masonry wall at one or both ends, normal stresses on the beam result in upward deflection of the ends of said beam or girder. Such deflection tends to overturn or crack the masonry wall into which the beam is framed. This is also true in cases where the floor or roof slab is cast of concrete and is framed directly into the masonry walls.

My invention therefore contemplates the provision of such a connection between the slab, beam or girder to the masonry wall, that the ends of the slab, girder or beam are free to deflect upwardly without over-stressing the wall and particularly without any danger of the wall's being cracked or overturned.

My invention further contemplates the provision of means for carrying the stresses in that part of the wall above the floor past the floor to the part of the wall below the floor whereby said means is stressed no further when the floor or floor parts are upwardly deflected at their ends.

My invention further contemplates the provision of spaces or recesses in the ends of the floor in which spaces or recesses are arranged, means for transmitting the weight of the wall above the floor to the wall part below the floor independently of the floor ends.

The various objects of my invention will be clear from the description which follows and from the drawing, in which,

Fig. 1 is a horizontal section and fragmentary plan view of a concrete floor slab and a supporting masonry wall therefor to which my invention has been applied.

Fig. 2 is a vertical section and partial elevation of the same.

Fig. 3 is a similar view of the means for bridging the space above a floor beam or a concrete slab resting on a wall.

In the practical embodiment of my invention the floor slab 1 which is here shown as being of concrete is suitably reinforced as by the reinforcing rods 13. Said slab is cast on the masonry wall 5 after said wall has been built to the required height. The wall 5 may be of brick, terra cotta, concrete block or any of the usual forms of construction, faced if desired or veneered by the brick or other facing 4.

In casting the slab 1 said slab is made discontinuous at its ends by the formation therein of

a series of spaced and inwardly directed recesses as 14 extending from the outermost edge 15 of the slab inwardly for a distance substantially equal to the thickness of the wall 5. The shape of the recesses 14 is immaterial but I prefer to make them substantially rectangular for convenience. The recesses 14 produce a series of spaced projections or tongues 16 on the ends of the slab, said tongues resting on and being supported by the wall 5.

Means in the nature of arches or the like are provided in the recesses 14 to bridge the space above and at both sides of the tongues 16. As shown in Figs. 1 and 2 said means takes the form of compression members such as upright piers, struts or columns 3 or columns each of somewhat greater height than the thickness of the floor slab, the space between said compression members being spanned by suitable horizontal members such as the blocks 8 resting on the short piers or columns. The members 3 and 8 may be made of brick, tile or other suitable floor or wall material and are set into place either before the casting of the floor slab 1 or after said slab has been cast as may be found convenient or desirable.

It should be understood that the materials and shapes here shown are for purposes of illustration only, and any other building materials or shapes may be substituted for those shown.

In the construction of the building the wall 5 is carried up to the level of the bottom of the floor slab 1 or to the level of the under face of the beam or girder 10. In the case where girders 35 are used in the floor system, the under surfaces of said girders rest at their ends on the adjacent top surface of the wall 5, the wall having an empty or hollow space therein around the end of the girder so as to leave said end free of the wall except at its under surface. Then the slab is cast or floor system or beams set. The slab is cast so that the tongues 16 fit loosely between the struts 3. Such loose fit may be accomplished by oiling the struts 3 before pouring the concrete for the slab, or by setting the struts 3 in place in an empty space therefor left in the wall, after the slab is poured. Space between the tongues 16 and the struts 3 may be filled with asphalt waterproofing material. Blocks 8 are then spanned across the struts 3 and the arch 7 laid over the blocks 8. The exact form of construction would to a large extent be determined by the loads to be carried by the wall, slab, beam or girder. The type and method of construction here indicated are for purpose of general illus-

tration of the invention. Thus, the struts 3 might be staggered on alternate floors so as not to be directly above one another, bearing plates may be placed under the beams or struts, and the beams or slabs may be anchored, preferably, to the wall. Thin anchor strips 11 may be inserted between the floor system and the wall in the space between the floor and arch 7. The reinforcement 12 transmits slab loads between the tongues 16. In the above construction it will be noted that upward deflection of the floor system at the wall will take place without overturning the wall, as a free space is provided between such system and the arch 7 or spanner 9.

I claim:

1. In a building construction, a masonry wall, a concrete floor slab, said slab having a series of spaced end slots therein, providing a series of spaced projections at the end of the slab, said wall having a space therein surrounding each of the projections, and means for supporting that portion of the wall above the slab comprising support members arranged in the slots and taking stress from the wall above the slab and transmitting said stress to the wall portion below the slab.
2. In combination, a masonry wall, a floor having spaced slots therein, those portions of the floor between the slots resting on the wall and the remaining part of the floor being free of the wall, said wall having a free space therein above each of said floor portions, and means for car-

rying the weight of that part of the wall above said floor portions to that part of the wall below the floor.

3. The combination with a wall, of a floor having spaced end projections, said wall having pockets formed therein for the reception of said projections, the height of each pocket being greater than that of the projection received thereby whereby the projection is capable of upward deflection within the pocket, and a supporting member for each of those parts of the wall above the respective pockets, said member having a horizontal part extending across the pocket and having vertically arranged parts resting on that part of the wall below the floor and thereby transferring the weight of that part of the wall above the pocket to that part of the wall below the floor.

4. In a building construction, a masonry wall having spaced pockets therein, floor members set into said pockets and of less height than that of the pockets, said members resting on the bottom surfaces of said pockets, said floor members being arranged in horizontal spaced relation, and means for supporting those portions of the wall above said floor members comprising a horizontal member spanning each of the pockets and vertical members supporting the horizontal member and resting on that part of the wall below the floor members.

MORRIS BERMAN.
